UNITED STATES PATENT OFFICE

132,741

DESIGN FOR A RADIO TELEPHONE TRANSMITTER AND RECEIVER OR SIMILAR ARTICLE

Cletus J. Collom, Detroit, Mich., assignor to
Weltronic Corporation, Detroit, Mich., a corporation of Michigan

Application March 20, 1942, Serial No. 196,270

Term of patent 14 years

To all whom it may concern:

Be it known that I, Cletus J. Collom, a citizen of the United States, residing in Detroit, in the county of Wayne, State of Michigan, have invented a new, original, and ornamental Design for a Radio Telephone Transmitter and Receiver or Similar Article, of which the following is a specification, reference being had to the accompanying drawing, forming a part thereof, wherein:

Figure 1 is a view in side elevation of a radio telephone transmitter and receiver or similar article embodying my new design, certain por-

tions of the design being shown in dotted lines;

Fig. 2 is a view in front elevation of the structure shown in Fig. 1; and

Fig. 3 is a view in rear elevation of the structure shown in Figs. 1 and 2.

The dominant features of my design reside in the portions thereof which are shown in full lines.

I claim:

The ornamental design for a radio telephone transmitter and receiver or similar article, as shown.

CLETUS J. COLLOM.
